PELT STRETCHING MACHINE

John J. Mowad, Newark, N. J.

Application February 10, 1949, Serial No. 75,570

5 Claims. (Cl. 69—33)

1

This invention deals with means for stretching pelts, and more specifically, to novel machines for two-directional stretching of pelts used in the hatters' fur and similar industries.

Among the novel features embodied in the present invention are rapid means for changing the rate of stretch by changing of only a few gears, also the prevention of sticking of pelts to the rolls and independent adjustment of pressure on each set of rolls. Other improvements include ready removal of the upper section of the machine without the necessity of disengaging belts or gears, easy adjustment of spacing of the rollers, and ready accessibility of all parts.

The invention will be more readily understood by reference to the drawings in which Figure 1 is a front view of one embodiment of a machine constructed in accordance with the present invention. Figure 2 is a rear view of the same machine. The right side view of the machine is illustrated in Figure 3, while Figure 4 is a partial top view showing the right portion of the machine. A cross-sectional view of the same machine, taken along line V—V of Figure 1 is depicted in Figure 5. Figure 6 is a side view showing the bearing box detail, while Figure 7 is a schematic drawing illustrating the stretching of a pelt as it is drawn through the machine. Similar numerals refer to similar parts in the various figures.

Referring again to the drawings, numerals 1 and 2 represent a pair of laterally-ribbed, counter-rotating rollers superimposed upon each other with ribs meshing so as to enable drawing therethrough of pelt 65 fed therebetween. These rollers are mounted at their ends on frame 18 attached to frame support 15 by means of bolts 17. Reinforcing cross bars 13 and 16 are disposed between supports 15. Behind rollers 1 and 2 are mounted, in tandem relation thereto, another pair of rollers 3 and 4, also superimposed on each other, counter-rotating, and ribbed in a similar manner to rollers 1 and 2 and rotating at a faster speed so that pelt 65 passing between rollers 1 and 2 is stretched lengthwise as it is picked up and drawn between rollers 3 and 4. The latter two rollers are preferably ribbed in herring-bone fashion as illustrated in the drawings, so that the pelt is also stretched sidewise as it is pulled between rollers 3 and 4.

Upper rolls 1 and 3 are also provided with circumferential grooves 60 and 61 cut around cylinders 1 and 3 respectively, and preferably of depth equal to the height of the ribs. These grooves are spaced close enough together to insure at least

one contacting the pelt to be stretched. This spacing may be about 3" to 6" apart, more or less. Mounted on the frames (which comprise the sides of the machine) are front finger bar 6 and rear finger bar 28 disposed above the upper rolls 1 and 3 respectively and somewhat outwardly from the centers thereof. Attached to said finger bars 6 and 28, and disposed downwardly are arms or front fingers 5 and rear fingers 29, respectively, the bottom tips of which ride in grooves 60 and 61 respectively, thereby enabling picking up of pelts which may have stuck to the upper rolls and would otherwise make another revolution around them, thereby causing damage to such pelts as well as others which may have been fed between the rolls in the interim. The front finger bar 6 is attached to support 20 which projects from bearing box top plate 19 attached to the top of frame 18. The rear finger bar 28 is attached to bar clamp 27 which is fastened to plate 30 by means of screw 15. Screw 14 is also provided for fixing the position of finger bar 28 (Fig. 6).

As can be seen in Fig. 6, the ends of the rollers 1, 2, 3 and 4 are provided with journals 21, 22, 23 and 24, respectively which are encased in bearing boxes 35, 36 and 37, the latter being provided with replaceable split bronze bushings 39 in which each of the shafts rotates. It will be observed that bearing box 37 (split lengthwise at 10) and resting on frame 18, is a single block encasing journals 22 and 24, while journals 21 and 23 are separately encased in bearing boxes 35 and 36 which are disposed over 37 and separated therefrom by spacer plate 38. Plate 18 which serves as a bearing box guide is mounted on frame 15 by means of bolts 17 and is provided with top plate 19 which is fastened to frame 18 and is provided with holes 71 through which or in which ride helical springs 32 and 32', a pair on each end of the machine for impressing a pressure upon the upper rolls. Due to the fact that bearing boxes 35 and 36 are separated at 12, it is possible to impose different pressures upon rolls 1 and 3. The upper portions of springs 32 which emerge above plate 19 are housed in hollow cylindrical sleeves or guides 31. These are covered by adjusting screw plate 30 which is held tight by bolt 63 screwed into plate 19, which bolt also holds in place guides 31 in grooves 73 in plate 19. Springs 32 are covered by pressure plate 68 on which pressure is transmitted by means of spring adjusting screws 33 provided with lock nuts 34.

Attached to side frame members or supports 15 (on each side of the machine) are base plates 41

(Fig. 3) on which are mounted the ends of adjustable arm 40 by means of bolts 44. The ends of arm 40 are provided with arcuate slots 74 in which bolts 44 ride. By this means it is possible to loosen bolts 44 and rotate arm 40 (to a limited extent, i. e. the limits of slots 74) with the center section of arms 40 acting as the center or axis of rotation.

At the center of rotation are mounted the ends of drive shaft 14 which project out from plates 40 and allow mounting thereon of gear 12. Alongside gears 12, and fixed to plate 40 (reversibly disposed on each side of the machine) is vertically directed arm 75, on the upper portion of which is mounted short shaft 42 carrying changeable gear 10 and gear 11 and provided with compound bushing 43. Gear 11 meshes with gear 12. Gear 10 may be changed and larger or smaller gears may be substituted, adjustment being made at the ends 74 of arm 40, corresponding to the size of the gear.

Journal 22 projects on one side of the machine and on said projection is mounted gear 9 which engages gear 10. Likewise, journal 24 extends from the other end of the machine and carries a similar gear, both gear trains being driven by drive-shaft 14.

Each pair of rolls is geared together on the opposite side from the driven gear train. For example, gears 7 and 8 are used to transmit rotary motion to roller 1 while gears 25, etc. act in the same manner for roller 3. Drive shaft 14 is provided with pulley 46 which is connected by a belt to pulley 47 of motor 48 mounted on lower cross-bars 16. Clamp 45 is attached to the end of shaft 42 to hold the gear in place after changing gears. Clamps 64 are mounted on the frame to hold the gear covers.

The front and rear of the machine are provided with tilttable tables 54 and 55 respectively (Fig. 5), which are not shown in Figs. 1 and 2. These are mounted on upper cross-bars 13 by table adjusting clamps 56 and bolts 57, the tables being of such height as to allow sliding of belts from the table directly between rolls 1 and 2. A finger guard 51 is also attached to guard assembly frame 49, allowing an adjustable feeding space which will not allow the fingers of the operator to contact the rolls. Top plate 50 is likewise mounted over guard assembly frame 49 to cover the upper roll sections (Fig. 4).

As can be seen from Fig. 7, the rough, wrinkled belts 65 are fed between rollers 1 and 2, and thence between faster rollers 3 and 4 which causes stretching at 66, the herringbone corrugations of rolls 3 and 4 also simultaneously stretching the belt sideways to deposit an overall stretched belt on rear table 55.

As is apparent from the foregoing, the machine of the present invention requires no manual labor on the part of the operator other than placing the belt on the front table and feeding it into the opening between the finger guard and the table, the belt being stretched without injury to the belt itself. By independent control of the pressure on each upper roll, the quality of the finished belt may be maintained. Since the gears are readily changeable in the gear trains, speeds may be adjusted to take care of any type of belt handled.

Although herringbone - grooved rollers are shown in the drawings for the rear pair (3 and 4), it is to be understood that a straight grooving of these rolls may be employed, similar to that employed on rollers 1 and 2.

Shaft 14 has its main bearings 15 fixed to the sides of the frame 15 by means of crossbars. Hence this shaft is not moved when plates 40 are moved or adjusted to accommodate different gears. Vertical movement of plate or arms 40 may be extended beyond the limits of arcuate slots 74 by providing additional holes in plate 41 through which bolts 44 may be inserted (above and below the positions of the bolts 44 shown in Fig. 3).

In the present machine, it is necessary to provide for slippage of belt 65 between the rollers in each pair of rollers, as otherwise tearing of the belt may take place. This slippage is controlled by adjusting the pressure on the upper rolls by compressing springs 32 and 32' as heretofore outlined.

For sake of clarity, the pairs of rollers illustrated in Figures 5 and 6 are not shown as meshing with each other. Actually, the rolls mesh as in Figure 7, but not tightly enough to clash to avoid excessive wear of roller surface.

I claim:

1. In a belt-stretching machine having a pair of superimposed laterally-ribbed, counter-rotating rollers, geared to each other for feeding therebetween the belt to be stretched, followed in tandem relation thereto by another pair of ribbed counter-rotating rollers, geared to each other for pulling the belt therebetween as said belt is discharged from the first pair of rollers, said second pair of rollers rotating at a speed faster than that of the first pair, a support attached to the ends of said rollers, and driving means for driving said rollers, the improvement comprising a cross-arm mounted substantially laterally across each side of the frame under the ends of said rollers, adjustable fastening means near the ends of each cross-arm enabling fastening said cross-arm to the frame in any position of said cross-arm after the latter has been moved within a fixed limit in an arc with the middle portion of the cross-arm acting as the center of rotation of said arc, a drive-shaft disposed between the cross-arms and having its ends mounted thereon at said center of rotation, a first gear mounted on each end of said drive shaft, a vertically disposed arm having its lower end fixed to each cross-arm adjacent the first gear, a short shaft mounted on the other end of the vertical arm and projecting outwardly, a second gear mounted on said short shaft in operating contact with the first gear, a third gear mounted on said short shaft alongside the second gear, and a fourth gear attached to the end of the lower of the nearest pair of rollers and in operating contact with the third gear, and power transmitting means from said driving means to said drive shaft, each second gear being offset under a different pair of rollers, with respect to the first gear, thereby enabling use of different gear ratios at each side of the frame to provide different speeds for each pair of rollers while using only one driving means and drive-shaft.

2. A belt stretching machine according to claim 1 in which the upper rolls are provided with circumferentially cut continuous grooves of depth substantially equal to the height of the ribs, a cross-bar mounted above each upper roll and parallel thereto and attached to the sides of the frame, and downwardly disposed fingers having their upper ends attached to said latter cross-bars and their lower ends riding in the grooves at the outer sections of the rolls to disengage any

pelts which may have begun a second revolution around said rolls.

3. A pelt stretching machine according to claim 1 in which the ends of the rolls are provided with shafts riding in bearing blocks, the two lower shafts being encased in one block and the upper two shafts being encased in separate blocks superimposed upon the first block.

4. A pelt stretching machine according to claim 3 in which the frame above the blocks is provided with cylinders fixed to the frame and disposed one over each upper block, a helical spring disposed within each cylinder with the bottom of the

5 spring resting on the block, and spring compressing means on the top of said cylinders for impressing a pressure on said blocks.

5. A pelt stretching machine according to claim 1 in which the frame is split just below the lower rolls into two sections, a lower and an upper, thereby allowing removal of the roll assembly without interference with the drive assembly, and fastening means to fasten the two sections together when desired.
